HANDRAILING

Wenzel W. Thom, Wichita, Kans., assignor of one-half to
Fannie May Jones, Wichita, Kans.

Filed Apr. 4, 1968, Ser. No. 11,299

Term of patent 14 years

Int. Cl. D25—02

U.S. Cl. D13—7

Fig.1.

Fig.3.

Fig.5.

FIG. 1 is a perspective view of a handrailing showing my new design;

FIG. 2 is a front elevational view thereof;

FIGS. 3 and 5 are cross-sectional views thereof taken on the lines 3-3 and 5-5 respectively of FIG. 2;

FIG. 4 is an elevational view of the post, showing my new design; and

FIGS. 6 and 7 are cross-sectional views thereof taken on the lines 6-6 and 7-7 respectively of FIG. 4.

I claim:

The ornamental design for a handrailing, as shown and described.
